METAL DOOR CONSTRUCTION

Harold A. Etling, Marshallville, Ohio, assignor to Weather-Seal, Inc., North Barberton, Ohio, a corporation of Ohio

Filed Oct. 10, 1958, Ser. No. 766,589

6 Claims. (Cl. 189—46)

This invention relates to metal doors, and especially to end and corner constructions for metal doors wherein the door frames are made from metal side, top and bottom stiles of about the same thickness, and usually of substantially the same cross sectional contour.

At the present time, several different types of metal doors are produced in large quantities and such doors frequently are used as auxiliary, or storm doors on building units. In all events, it is desirable that these doors have sturdy, well built frames and that the doors hold their shapes over extended periods of rough use. Naturally the costs of the doors are important in determining the practicality of the doors for many purposes and so the production of a strong, low cost door is very desirable. In general, these doors are made from extruded metal shapes, usually of hollow, rectangular shape in section. Frequently components of the frames for the doors have been secured together by welding suitable reinforcing or connector angles at the corners of the frame, or by gussets. Welding is a costly process and frequently leads to metal failures or breakage. Angles and gussets may work loose in use.

The present invention has as a general object the provision of an improved strength metal door characterized by the provision of special reinforcing members at the corners of the door.

A further object of the invention is to provide a corner in a metal door where the door is made from hollow metal stiles secured together by a mortise and tenon type joint and by integral end flaps on the outer of the two stiles.

Another object of the invention is to provide a metal door with certain assembly joints therein substantially hidden from view.

Another object of the invention is to cut away or otherwise remove a portion of the inner side wall on door stiles so that a reduced thickness end of another stile can be telescoped into engagement with the first stile through the opening provided therein, be abutted against the remaining side wall of such first stile, and be anchored tightly in such position.

The foregoing and other objects and advantages of the invention will be made more apparent as the specification proceeds.

Reference now should be had to the accompanying drawings, wherein:

Fig. 1 is an elevation of a metal door embodying the principles of the invention;

Fig. 2 is an enlarged plan of a section of the top cross stile of the door of Fig. 1;

Fig. 3 is a rear elevation of the top stile shown in Fig. 2;

Fig. 4 is a fragmentary enlarged elevation of the end portion of a side stile of the door of Fig. 1;

Fig. 5 is a right side elevation of the stile section shown in Fig. 4;

Fig. 6 is an enlarged perspective view of a corner of the door of Fig. 1;

2

Fig. 7 is an enlarged elevation of a corner of a door embodying a modification of the door of the invention;

Fig. 8 is a fragmentary vertical section taken on line 8—8 of Fig. 6; and

Fig. 9 is a fragmentary vertical section taken on line 9—9 of the door of Fig. 6.

When referring to corresponding parts shown in the drawings and referred to in the specification, corresponding numerals are used to facilitate comparison therebetween.

When referring to doors in this specification, house doors, as well as commercial doors, garage doors, and the like, are all meant to be included within the scope of such term, and the doors may be used as screen and/or storm doors, and as primary or auxiliary doors, as desired.

Broadly speaking, the present invention relates to a door comprising hollow metal side stiles, a metal top stile, and a hollow metal bottom stile, where all of the stiles have top and bottom walls and inner and outer side walls and usually are of rectangular shape and the same general size in section. The side stiles are overlapped with the top and bottom stiles at the corners of the door, and one of the stiles at each corner of the door has an inner side wall thereon removed and the other of the stiles at such corner is of reduced thickness at the end thereof and is received within the other stile through the opening provided by the removed side wall therein, rivet or equivalent means extend through or otherwise secure the overlapped ends of the stiles together at the corners of the door and end flaps on the outer stile at each corner of the door are folded over the inner stile and secured to a side wall thereof so that a sturdy, but inexpensive metal door is provided.

Reference now is particularly directed to the details of the embodiment of the invention shown in the accompanying drawings, and a door 1 is indicated therein. The door 1 includes conventional panels, such as glass or screen panels 2 and 3 and a kick panel 4 therein, which panels are secured in place in a conventional manner. The door 1 includes a frame indicated as a whole by the numeral 5 and made from a top stile 6, a bottom stile 7, and side stiles 8 and 9. All of these stiles 6 through 9 are made from metal and are normally of the same hollow, rectangular shape and size in section. The surfaces shown on the face of the door in Fig. 1 are considered to be the top walls thereof for describing the door parts so that a top wall 10 and a bottom wall 11 are provided on the top stile 6 which also has an inner side wall 12 and an outer side wall 13 provided thereon. Likewise, the side stile 8 has a top wall 14, a bottom wall 15, an inner side wall 16 and an outer side wall 17.

As a feature of the invention, the end of the top stile 6 is of reduced thickness, as best shown in Fig. 3 and as indicated at 6a. The end 6a is of such thickness as to be received snugly within the side stile 8 intermediate the top and bottom walls 14 and 15 thereof. So as to receive the top stile end 6a therein, an opening 18 is formed in the inner side wall 16 of the side stile 8 adjacent the end thereof. Such opening or aperture 18 is provided by removing a portion of the inner side wall from the stile usually by some cutting or punching operation. Preferably both the top and bottom walls 10 and 11 of the top stile 6 are forced inwardly of the stile equal distances so that the center axis of the top stile 6 will still align with the center axis of the side stile 8, or other member to which the top stile is to be engaged or secured. These center axes of the stiles define a center plane in the door.

It should be noted that the top stile 6 is inserted into the side stile 8 until the end of the top stile abuts against

the inner surface of the outer side wall 17 of the side stile. This aids in accurately and automatically setting the top stile and side stile at exactly a right angular relationship to each other and also reenforces the joint produced therebetween. The top stile 6 usually abuts against the lower edge of the opening 18.

Figs. 4, 5 and 9 best show that the laterally outer wall 17 of the side stile 8 is spaced inwardly of the stile. Edge flanges 19 and 20 extend from and reenforce the stile 8 along such outer wall 17. Fig. 5 illustrates that the wall 17 and usually the flanges 19 and 20 are cut off or otherwise removed for a short distance at the end of the side stile 8 to form end flaps 21 and 22 on the stile. It is an important feature of the invention that the end flaps 21 and 22 are folded over the top stile 6 and are riveted to the side wall 13 thereof by rivets 23. Suitable holes are provided in the end flaps 21 and 22 and in the side wall 13 for receiving the rivets 23, that are of the so-called "blind" rivet type. It would be possible to secure the end flaps 21 and 22 in other conventional manners, as by welding, to the side stile 8.

A flange 24 usually is formed integrally with the top stile 6 and may terminate spaced axially from the reduced thickness end section 6a, while a similar flange 25 is provided on the side stile 8 and it extends to the opening 18 provided therein so that these flanges will not interfere with each other when the stiles are brought into engagement to form a corner on the door. The flanges 24 and 25 are used to aid in determining the position of the panels 2 through 4 of the door and other means (not shown) of any conventional construction can be used to secure these panels in position on the door and against the flanges 24 and 25.

Cross stiles 26 and 27 are also provided in the door 1 intermediate the top and bottom stiles 6 and 7. These cross stiles 23 and 24 may have reduced thickness end sections, if desired, and be received in openings provided in the inner side walls of the side stiles 8 and 9. The cross stiles may be cemented or welded in position.

A modified type of a door corner construction, indicated as a whole at 26, is shown in Fig. 7 and this comprises another embodiment of the door means of the invention. In this instance, each of the stiles 6a and 8a has a contoured flange 30 provided thereon that provides a shoulder (not shown) used for positioning an insert panel 31 in the door. It will be seen in Fig. 7 that the adjacent ends of these flanges 30 are beveled at complementary 45° angles to provide a neat, tight fit between the stiles at the corner of the door.

It also is possible to reinforce the joint between the overlapped stile ends in the metal doors of the invention by a cementing or bonding action. Thus commercial products, such as "Tygo-Weld," "36-B," and the Activator for 41 therefor, made by U.S. Stoneware Company of Akron, Ohio, is a typical commercial cement used to bond metal-to-metal by the present invention. This adhesive is an alloyed epoxy base structural adhesive and equivalent materials may be used in lieu thereof. The top and bottom walls 10 and 11 of the top stile 6 would be immediately adjacent the inner surfaces of the top wall 14 of the bottom wall 15 of the side stile 8 and can be bonded thereto by a liquid sealing medium that solidifies in place for a bonding action.

It should be noted that the inner side walls of the inner of the stiles at a door corner may be removed or not as desired.

The end flaps 21 and 22, or equivalents may be provided on the top, side or bottom stiles as preferred in any given door construction. Preferably the inner stile end fits snugly into the outer stile and abuts on a side wall of the outer stile to aid in providing a sturdy, rigid door.

The construction of the invention may be used in making window sashes or other articles where a strong corner joint between metal members is required.

The end flaps 21 and 22 may be of any suitable width and length. Usually the end flaps are of the width of the stile on which they are formed.

From the foregoing, it will be seen that an improved style of corner construction and frames for doors is provided by the invention. The invention is particularly adapted for use with hollow metal door stiles made by extruding them to a desired contour and where the door members are of the same thickness and usually are of the same shape and size in section. The door construction can be readily formed and the components are easily assembled in proper relationship with each other and can be secured together by conventional means to form sturdy, but inexpensive and attractive doors that will hold their shapes and rigidity over long periods of use. Thus it is believed that the objects of the invention have been achieved.

While two complete embodiments of the invention have been disclosed herein, it will be appreciated that modification of these particular embodiments of the invention may be resorted to without departing from the scope of the invention as defined in the appended claims.

What is claimed is:

1. In a door comprising hollow metal side stiles, a hollow metal top stile, a hollow metal bottom stile, all of said stiles having top and bottom walls and inner and outer side walls and being of rectangular shape and the same size in section, said side stiles being overlapped with the top and bottom stiles at the corners of the door, one of said stiles at each corner of the door having the inner side wall thereon removed and the other one of said stiles at each said corner being of reduced thickness at the end thereof to be received within said first stile through the opening provided by the removed side wall therein, the improvement comprising the said stile of unreduced end thickness having a pair of end flaps extending therefrom from the top and bottom walls thereof, said end flaps being shaped to lie against the outer surfaces of the side wall of the other of said stiles, and rivet means securing the end flaps to the other of said stiles.

2. In a door comprising hollow metal side stiles, a hollow metal top stile, a hollow metal bottom stile, all of said stiles having top and bottom walls and inner and outer side walls and being of the same general shape and size in section, said side stiles being overlapped with the top and bottom stiles at the corners of the door, one of said stiles at each corner of the door having the inner side wall thereon removed and the other one of said stiles at each said corner being of reduced thickness at the end thereof to be received within said first stile through the opening provided by the removed side wall therein, the improvement comprising the said stile of unreduced end thickness having a pair of end flaps extending therefrom from the top and bottom walls thereof, said end flaps being shaped to lie against the outer surfaces of the side walls of the other of said stiles, and means securing together at the corner at the adjacent portions thereof.

3. In a door comprising hollow metal side stiles, a hollow metal top stile, a hollow metal bottom stile, all of said stiles having top and bottom walls and inner and outer side walls and being of rectangular shape and the same size in section, said side stiles being overlapped with the top and bottom stiles at the corners of the door, one of said stiles at each corner of the door having the inner side wall thereon removed and the other one of said stiles at each said corner being of reduced thickness at the end thereof to be received within said first stile through the opening provided by the removed side wall therein, the improvement comprising the said stile of unreduced end thickness having a pair of end flaps extending therefrom from the top and bottom walls thereof, said end flaps being shaped to lie against the outer side wall of the other of said stiles and substantially cover

such outer side walls, and means securing the overlapped end flaps and adjacent surfaces of the top and bottom walls of the stiles together at the corners of the door.

4. A door comprising hollow metal side stiles, a hollow metal top stile, a hollow metal bottom stile, all of said stiles having top and bottom walls and inner and outer side walls and being of quadrilateral shape and the same size in section, said side stiles being overlapped with the top and bottom stiles at the corners of the door, at least one of said stiles at each corner of the door having the inner side wall thereon removed and the other of said stiles at each said corner being of reduced thickness and of a size to be received within the other stile through the openings provided by the removed side wall therein, the said stile with a reduced thickness end being abutted against the inner surface of the outer side wall of the other of said stiles at the corner and having top and bottom walls lying immediately adjacent corresponding top and bottom walls of the other of said stiles, the said stile with a normal size end thereon having end flaps formed on the top and bottom walls thereof lying against the outer side wall of said reduced thickness end stile to substantially enclose such end stile, and rivet means securing said end flaps to said side walls at the corners of the door.

5. A generally planar shaped door, window or the like comprising hollow metal side stiles, a hollow metal top stile, a hollow metal bottom stile, all of said stiles having top and bottom walls and inner and outer side walls and being of the same general size, said side stiles being overlapped with the top and bottom stiles at at least one corner of the door, at least one of said stiles at said corner of the door having the inner side wall thereon removed and the other of said stiles at said corner being of reduced thickness and of a size to be received within the

other stile through the opening provided by the removed side wall therein, the said stile with a normal size end thereon having end flaps formed on the top and bottom walls thereof lying against a side wall of said reduced thickness end stile, and rivet means securing said end flaps to said side wall at the corner of the door, said rivet means being hidden from view from the front and back of the door.

6. A door comprising hollow metal side stiles, a hollow metal top stile, a hollow metal bottom stile, all of said stiles having top and bottom walls and inner and outer side walls and being of quadrilateral shape and the same size in section, said side stiles being overlapped and in telescopic engagement with the top and bottom stiles at the corners of the door, at least one of said stiles at each corner of the door having the inner side wall thereon removed and the other of said stiles at each said corner being of reduced thickness and of a size to be received within the other stile through the opening provided by the removed side wall therein, the said stile with a reduced thickness end being abutted against the inner surface of the outer side wall of the other of said stiles at the corner, the said stile with a normal size end thereon having integral end flanges formed on the top and bottom walls thereof lying against the outer side walls of said reduced thickness end stile, and means securing said end flanges to said side walls at the corners of the door to provide a sturdy reenforced overlapped stile joint at all corners of the door.
